United States Patent Office

Des. 181,242
Patented Oct. 15, 1957

181,242

CAN OPENER

Henry J. Talge, Kansas City, Mo., assignor to John C. Hockery, Kansas City, Mo., trustee for Henry J. Talge and Foster L. Talge

Application February 25, 1957, Serial No. 44,984

Term of patent 14 years

(Cl. D22—2)

Fig. 1 is a side elevational view of a can opener embodying my new design;

Fig. 2 is a plan view of same;

Fig. 3 is a front end elevational view of same; and

Fig. 4 is a perspective view of same taken from the side opposite that shown in Fig. 1.

I claim:

The ornamental design for a can opener, as shown.
